UNITED STATES PATENT OFFICE.

ARBA G. WILLIAMSON, OF CARNEGIE, PENNSYLVANIA, ASSIGNOR TO PITTSBURGH TRAIN CONTROL COMPANY, OF PITTSBURGH, PENNSYLVANIA, A CORPORATION OF DELAWARE.

TRACK-CIRCUIT SYSTEM.

Application filed April 5, 1922. Serial No. 549,661.

This invention relates to track circuit systems, particularly for use in connection with train control systems of the type disclosed in application Ser. No. 555,304 filed

5 April 18, 1922.

In systems of the character indicated in that application the train is provided with two pick-up circuits one of the indirect type and the other of the direct type and the 10 main object of this invention is to provide means whereby a circuit may be established including both rails of a block in series and whereby also another circuit may be established between one rail and ground to properly coordinate the indirect and direct pick-up circuits on the train with track equipment. Or the second circuit may be between the two rails in multiple and ground.

A further object of the invention is to 20 provide means whereby the circuit between one rail or the two rails in multiple and ground, is so arranged that existing track circuits may be used with but slight alteration.

25 Other features of the invention will appear as the specification proceeds.

In the accompanying drawings the invention is shown in several concrete and preferred forms in which

30 Fig. 1 is a diagrammatic view showing one well known form of track circuit with one form of the additional equipment of the invention applied thereto.

Fig. 1^a is a diagrammatic view showing 35 the two rails connected in parallel.

Fig. 2 is a diagrammatic view showing a second form of track circuit with another form of the additional equipment of the invention applied thereto.

40 Fig. 3 is a diagrammatic view showing a third form of track circuit with a third form of the additional equipment of the invention applied thereto.

Some of the claims in this application are 45 broad enough to cover all three forms of the invention shown as well as other forms in which the invention may be clothed, but the particular forms of Figs. 2 and 3 have been made the subject matter of two other 50 applications, Ser. No. 549,662 filed April 5, 1922 and Ser. No. 165,603 filed February 3, 1927, in which these forms are specifically claimed.

Referring to Fig. 1, 1 and 2 represent the

rails of a traffic track divided into blocks 55 W, X, Y and Z in a manner well understood as by means of insulation 3, 4 and 5 indicate line wires fed by the single frequency generator G. Associated with each block is a main transformer indicated by T^w, T^x 60 and T^y and the secondary 6 of each of those transformers is connected by means of conductors 7 and 9 with primary 8 of a track transformer indicated variously as N^w, N^x and N^y. Secondary 13 of the track transformer is connected by means of leads 16 and 17 with rails 1 and 2 thereby supplying current to both of said rails of a given block. These elements together with a relay such as rx, ry or rz constitute the ordinary 65 track circuit. Connected in parallel with the track transformer is a subsidiary transformer indicated at M^w, M^x and M^y, the primary 11 of which is connected by wires 10 and 12 with conductors 7 and 9, and this 70 subsidiary transformer feeds a circuit connected to one or both rails in multiple and ground, which circuit here is as follows: connected with one side of secondary 18 is a conductor 19 which is grounded; and connected with the other side of secondary 18 is a conductor indicated by wires 20, 23 and 25, the latter connected to lead 16. 15 and 24 indicate impedances, one for the track 75 circuit and the other for the rail and ground circuit. 21 is a circuit breaker interposed in the rail and ground circuit and this circuit breaker is actuated by signal S, of the preceding block, by suitable connections as a.

Normally current will flow in the rails of the track circuit fed by track transformer N and current will also flow from secondary 18 over wire 20, circuit breaker 21, wire 23, impedance 24, wire 25, wire 16, rail 1, 80 ground, and wire 19 back to secondary 18. It will be understood that rail 1 is not 85 grounded but may in fact be insulated from the ground. That is to say the insulation is of course not perfect and there exists a leakage of current but not excessive so that voltage above ground potential is maintained on the rail. If the rail was actually 90 grounded it would not be possible to maintain this voltage and consequently the direct 95 pick-up circuit would not receive an impulse. When, therefore, a train as K' enters a block 100 under normal conditions the indirect and

direct pick-up circuits carried by the train will both be influenced. The effect of the presence of a train as at K in block Z on the succeeding block Y will be readily understood. Such train will short circuit the track circuit thereby actuating signal S^z and deenergizing relay r^z and will thereby move circuit breaker 21^y against stop 22 thereby rupturing the rail and ground circuit of block Y and a train in block Y would therefore not have its direct pick-up circuit influenced, but would nevertheless have its indirect pick-up circuit influenced because the track circuit of block Y is not affected by the presence of a train in block Z. Should a second train advance from block Y into the occupied block Z it is clear that such second train would not have either its indirect or its direct pick-up circuits influenced. By "indirect" pick-up circuit is meant a circuit on the train in inductive relation to the current in the rails and by "direct pick-up circuit" is meant a circuit on the train of an electrostatic character, that is: there is a device on the train in circuit with one or more rails and having a capacity between itself and ground.

In Fig. 1^a is disclosed a modification in which wire 25 instead of connecting with 30 16 leads to a high resistance 100 bridging the rails so that rails 1 and 2 are connected in parallel with transformer M.

Referring to Fig. 2 the subsidiary transformer is omitted but interposed between 35 secondary 6 of the main transformer and primary 8 of the track transformer is a circuit breaker in the form of a pole changer P^w , P^x and P^y and connected to wire 7 between the pole changer and secondary 6 is 40 conductor 101, impedance 102, and wire 103 grounded at 104. Also connected between wires 7 and 14 is a shunt 105 around the track transformer. The pole changer may be controlled either from a signal or a relay. 45 In this case it is controlled from the signal, and a relay L^x , L^y and L^z which is of the two element type being influenced both by the track circuit and by current from transformer T in a manner to be presently described. Q indicates a winding affecting 50 relay L, this winding being connected to wires 7 and 9 and therefore fed by transformer T. Accordingly one element of relay L receives current from the track circuit and the other element Q from the main transformer. It is well known that when the instantaneous polarity of both elements is such that the currents in both elements are in phase then armature 100 will swing to 55 right hand position. If the connections of one element should be reversed so that the instantaneous polarity of the currents in the two elements are out of phase then armature 100 will swing to the left hand position. 60 If current is absent in the track element then

armature 100 will hang in center position. Reversal of the instantaneous polarity of the current in the track rails is accomplished by the pole changer reversing the connections to the primary of the track transformer, the pole changer being here operated by the signal mechanism. It is further well known that when signal S^z is at stop or danger position then pole changer P^y is moved to the left hand position, in which 70 position the instantaneous polarity of the current in rails of block Y is out of phase with that of element Q^y and armature 100 of relay L^y will therefore assume its left hand position and signal S^y will therefore 75 assume caution position. Signal S^y , when moving into caution position, will move pole changer P^x from left to right hand position, and the polarity of the current in the rails of block X being now such in 80 respect to element Q^x that armature 100 of relay L^x will assume its right hand position and therefore signal S^x will move to clear. When this occurs signal S^x will not move pole changer P^w to any new position but 85 said pole changer will occupy the same position as it did under caution conditions. Assuming now that a train proceeds in the direction indicated by the arrow, it will be understood that so long as current is flowing 90 in the track circuit the indirect pick-up circuit on the train will be influenced and it is only when a train enters a block such as Z, already occupied by another train, that the indirect pick-up circuit is not influenced by 95 the track circuit.

When a train K occupies block Z then pole changer P^x will occupy its right hand position and current from secondary 6 of transformer T^x will be supplied to the rail and ground circuit as follows: secondary 6, conductor 7, conductor 101, impedance 102, conductor 103, ground 104, rail 1, conductor 14, shunt 105, conductor 7, pole changer P^x conductor 9, and back to secondary 6. The 105 direct pick-up circuit of a train entering block X will therefore be influenced. In block Y, however, pole changer P^y is in the left hand position and therefore that side of secondary 6 of transformer T^y which is connected to ground is also connected to rail 1 of block Y and therefore no current from secondary 6 flows through the rail and ground circuit. Therefore the direct pick-up circuit of the train will not be influenced.

Referring now to Fig. 3, here the track circuits are energized by a direct current supplied by battery 150 connected to the rails by leads 118 and 117, this current normally energizing relay 151 (marked with an exponent similar to the block designations) controlling armatures 143 and 152. The current supplied for influencing the indirect and direct pick-up circuits of the train is supplied by a battery 110 and an interrupter 115 120 125 130

- 106 (marked with an exponent similar to the block designations) actuated by motor 107. The interrupter current supplied to the two rails of the track and adapted to influence the indirect pick-up circuit of the train is impressed on the rails in the following manner: from battery 110 by wire 111, armature 112, wire 114, interrupter 106^x, wire 115, resistance 116, lead 117, rail 1 of block X, 10 across the train to rail 2, lead 118, wire 157, armature 120 and wire 121 back to battery 110. Bridging wires 115 and 118 is the primary 122 of a transformer 123, the secondary 124 of which is interposed in a rail and 15 ground circuit composed of said secondary, wire 125, resistance 126, wire 145 and ground on one side of said secondary; and wire 141, armature 143, wire 144 and wire 118 to rail 2 on the other side of the secondary. This 20 current will influence the direct pick-up circuit carried by the train. 109 indicates a relay controlling armatures 112 and 120 and this relay is normally deenergized so long as relay 151^x of the succeeding block is energized. But when a train enters block X from block W relay 151^x will be deenergized thereby causing armatures 152 and 143 of relay 151^x to drop. When this occurs a circuit is established through back contact 108^x 25 as follows: from 108^x to wire 153, to relay 109, wire 155, wire 146; battery 110^x and wire 156 to contact 108^x. This picks up armatures 112 and 120 and establishes a circuit through motor 107^x as follows: from battery 110, 30 wire 111, armature 112, wire 114, motor 107^x, wire 157, armature 120 back to battery 110. It also establishes the previously described circuit through interrupter 106^x. Thus when 35 no train is in block X no current to affect 40 either the indirect or the direct pick-up circuit is supplied.

When a train enters block Y and a train K is present in block Z the rail and ground circuit is ruptured owing to the deenergization 45 of relay 151^x and if the train enters blocks Z with another train already in the block no current will be received by said second train.

It will thus be seen that in all the forms 50 of this invention as shown in Figs. 1, 2 and 3 two circuits are present, one for the indirect and the other for the direct pick-up circuit on the train and that a circuit breaker is interposed in that circuit of the two which 55 is between rail and ground and that this circuit breaker is controlled from a preceding block.

By the expression "pulsating" current used in the accompanying claims it is intended 60 to comprehend both an alternating or oscillating current or an interrupted or fluctuating direct current.

I claim:

1. A track circuit system comprising: traffic rails divided into blocks, a circuit in- 65

cluding both rails in series, a circuit, connected to ground at one side and to at least one of the rails at its other side, for maintaining voltage above ground potential on at least one of said rails, and a circuit breaker included in said second circuit and controlled by the first circuit of a preceding block. 70

2. A track circuit system comprising: traffic rails divided into blocks, a circuit in- 75

cluding both rails in series, a circuit, connected to ground at one side and to at least one of the rails at its other side, for maintaining voltage above ground potential on at least one of said rails, a circuit breaker 80 included in said second circuit and controlled by the first circuit of a preceding block, and a single current source supplying current to both of said circuits.

3. A track circuit system comprising: traffic rails divided into blocks, a circuit in- 85

cluding both rails in series, a circuit, connected to ground at one side and to at least one of the rails at its other side, for maintaining voltage above ground potential on at least one of said rails, a circuit breaker 90 included in said second circuit and controlled by the first circuit of a preceding block, and means for supplying pulsating current to said circuits. 95

4. A track circuit system comprising: traffic rails divided into blocks, a circuit in- 100

cluding both rails in series, a circuit, connected to ground at one side and to at least one of the rails at its other side for maintaining voltage above ground potential on at least one of said rails, a circuit breaker included in said second circuit and controlled by the first circuit of a preceding block, and a single current source supplying pulsating current to both of said circuits. 105

5. A track circuit system comprising: traffic rails divided into blocks, a circuit between the two rails of a block and including two leads from a current source bridging the 110 rails, a second circuit between ground and at least one of said rails including a conductor connected to one of said leads and another conductor connected to ground for maintaining voltage above ground potential 115 on at least one of said rails; and a circuit breaker interposed in said second circuit between the two conductors.

6. A track circuit system comprising: traffic rails divided into blocks, a circuit between the two rails of a block and including two leads from a current source bridging the rails, a second circuit between ground and at least one of said rails including a conductor connected to one of said leads and another conductor connected to ground for maintaining voltage above ground potential 120 on at least one of said rails and means for controlling said second circuit from the first circuit of a preceding block. 125

7. A track circuit system comprising: traffic rails divided into blocks, a circuit including both rails in series, a circuit, connected to ground at one side and to at least one of the rails at its other side, for maintaining voltage above ground potential on at least one of said rails, and means for controlling said second circuit from the first circuit of a preceding block.
10. 8. A track circuit system comprising: traffic rails divided into blocks, a circuit including both rails in series, a circuit, connected to ground at one side and to at least one of the rails at its other side, for maintaining voltage above ground potential on at least one of said rails, a single current source supplying current to both of said circuits and means for controlling said second circuit from the first circuit of a preceding block.
15. 9. A track circuit system comprising: traffic rails divided into blocks, a circuit including both rails in series, a circuit, connected to ground at one side and to at least one of the rails at its other side, for maintaining voltage above ground potential on at least one of said rails, means for supplying pulsating current to said circuits, and means for controlling said second circuit from the first circuit of a preceding block.
20. 10. A track circuit system comprising: traffic rails divided into blocks, a circuit including both rails in series, a circuit, connected to ground at one side and to at least one of the rails at its other side, for maintaining voltage above ground potential on at least one of said rails, a single current source supplying pulsating current to both of said circuits, and means for controlling said second circuit from the first circuit of a preceding block.
25. 11. A track circuit system comprising: traffic rails divided into blocks, a circuit between the two rails of a block, a circuit between ground and at least one of said rails for maintaining voltage above ground potential on at least one of said rails, a track transformer feeding the first circuit, a subsidiary transformer feeding the second circuit, and a main transformer feeding the track and subsidiary transformers.
30. 12. A track circuit system comprising: traffic rails divided into blocks, a circuit between the two rails of a block, a circuit between ground and at least one of said rails for maintaining voltage above ground potential on at least one of said rails, two transformers arranged in parallel one feeding the first circuit and the other feeding the second circuit, a main transformer feeding the track and subsidiary transformers, and a circuit breaker in said second circuit.
35. 13. A track circuit system comprising: traffic rails divided into blocks, a circuit between the two rails of a block, a circuit between ground and at least one of said rails for maintaining voltage above ground potential on at least one of said rails, two transformers arranged in parallel one feeding the first circuit and the other feeding the second circuit, a main transformer feeding the track and subsidiary transformers, and a circuit breaker in said second circuit.
40. 14. A track circuit system comprising: traffic rails divided into blocks, a circuit between the two rails of a block, a circuit between ground and at least one of said rails for maintaining voltage above ground potential on at least one of said rails, a track transformer feeding the first circuit, a subsidiary transformer feeding the second circuit, a main transformer feeding the track and subsidiary transformers, and means for controlling the second circuit from the first circuit of a preceding block.
45. 15. A track circuit system comprising: traffic rails divided into blocks, a circuit between the two rails of a block, a circuit between ground and at least one of said rails for maintaining voltage above ground potential on at least one of said rails, two transformers arranged in parallel one feeding the first circuit and the other feeding the second circuit, a main transformer feeding the first two transformers, and means for controlling the second circuit from the first circuit of a preceding block.
50. 16. A track circuit system comprising: traffic rails divided into blocks, a circuit between the two rails of a block, a track transformer feeding said circuit, a subsidiary transformer, a conductor between said subsidiary transformer and said circuit, another conductor between said subsidiary transformer and ground for maintaining voltage above ground potential on at least one of said rails, a main transformer feeding the track and subsidiary transformers, and means for controlling the circuit including the two conductors and the subsidiary transformer from the first circuit of a preceding block.
55. 17. A track circuit system comprising: traffic rails divided into blocks, a circuit between the two rails of a block, a circuit between ground and at least one of said rails for maintaining voltage above ground potential on at least one of said rails, a track transformer feeding the first circuit, a subsidiary transformer feeding the second circuit, a main transformer feeding the track and subsidiary transformers, and a circuit breaker in said second circuit.
60. 18. A track circuit system comprising: traffic rails divided into blocks, a circuit between the two rails of a block, a circuit between ground and at least one of said rails for maintaining voltage above ground potential on at least one of said rails, two transformers arranged in parallel one feeding the first circuit and the other feeding the second circuit, a main transformer feeding the track and subsidiary transformers, and a circuit breaker in said second circuit.

ing the first two tranformers, and a circuit breaker in said second circuit.

19. A track circuit system comprising: traffic rails divided into blocks, a circuit between the two rails of a block, a track transformer feeding said circuit, a subsidiary transformer, a conductor between said subsidiary transformer and said circuit, another conductor between said subsidiary transformer and ground for maintaining voltage above ground potential on at least one of said rails, a main transformer feeding the track and subsidiary transformers, and a circuit breaker in one of the two conductors.

16 20. A track circuit system comprising: traffic rails divided into blocks, a circuit between the two rails of a block and including two leads from a current source bridging the rails, a second circuit between ground and at least one of said rails for maintaining voltage above ground potential on at least one of said rails including a conductor connected to one of said leads and another conductor connected to ground, and a circuit breaker interposed in said second circuit between the two conductors and controlled by traffic conditions of a preceding block.

21. A track circuit system comprising: traffic rails divided into blocks, a circuit between the two rails of a block and including two leads from a current source bridging the rails, a second circuit between ground and at least one of said rails for maintaining voltage above ground potential on at least one of said rails including a conductor connected to one of said leads and another conductor connected to ground, and means

for controlling said second circuit by traffic conditions of a preceding block.

40

22. A track circuit system comprising: traffic rails divided into blocks, a circuit including both rails in series, a circuit, connected to ground at one side and to at least one of the rails at its other side, for maintaining voltage above ground potential on at least one of said rails, and means for controlling said second circuit by traffic conditions of a preceding block.

45

23. A traffic circuit system comprising: traffic rails divided into blocks, a circuit between the two rails of a block, a circuit between ground and at least one of said rails for maintaining voltage above ground potential on at least one of said rails, a track transformer feeding the first circuit, a subsidiary transformer feeding the second circuit, a main transformer feeding the track and subsidiary transformers, and means for controlling the second circuit by traffic conditions of a preceding block.

55

24. A track circuit system comprising: traffic rails divided into blocks, a circuit between the two rails of a block and including two leads from a current source bridging the rails, and a second circuit between ground and at least one of said rails for maintaining voltage above ground potential on at least one of said rails including a conductor connected to one of said leads and another conductor connected to ground.
